UNITED STATES PATENT OFFICE.

FRANKLIN HARDINGE, OF OAK PARK, ILLINOIS, ASSIGNOR TO HARDINGE BROTHERS,
OF CHICAGO, ILLINOIS, A CORPORATION OF ILLINOIS.

COUNTER-SHAFT.

1,311,969.

Specification of Letters Patent.

Patented Aug. 5, 1919.

Application filed January 26, 1918. Serial No. 213,866.

To all whom it may concern:

Be it known that I, FRANKLIN HARDINGE, a citizen of the United States, residing at Oak Park, in the county of Cook and State 5 of Illinois, have invented a certain new and useful Improvement in Counter-Shafts, of which the following is a full, clear, concise, and exact description, reference being had to the accompanying drawings, forming a part 10 of this specification.

My invention relates to countershafts. In shops where a number of machines, lathes, and the like are in use it has been customary to arrange the machines in rows, operating 15 each row of machines from an associated countershaft having its independent supports and bearings. It is an object of my invention to provide a countershaft construction arranged for disposition between 20 machines having their backs to each other, so that driving connection may be had between the countershaft and the machines. The preferred form of my device consists 25 essentially of a pair of shafts each carrying suitable pulleys for connection between the driving means and the machines, the shafts being mounted co-axially in three bearings one of which is located at the point where 30 two of the shaft ends meet, and the other two at the opposite ends of the shaft, the middle bearing support being held in alined position by a rigid frame structure extending between the two end bearings. Although contained in a unitary structure each 35 shaft with its connected members is operable independently of the other, so that it is possible to drive different machines from the one device.

My invention will be understood by reference to the accompanying drawings, in which—

Figure 1 is an assembled view of the countershaft of my invention;

Fig. 2 is a vertical sectional view of the 45 device;

Fig. 3 is an enlarged sectional detail view of the central bearing;

Fig. 4 is a sectional view taken on the line 4—4 of Fig. 1;

Fig. 5 is an end view of my device showing its disposition between two benches each carrying a bench lathe; and

Fig. 6 is a side view of the structure shown in Fig. 5.

Similar characters of reference refer to

similar parts throughout the several views.

Referring first to Fig. 1 the countershaft construction consists of a pair of hangers 10, 11 having sleeves 12, 12 and 13, 13 on each side arranged to receive supporting means, 60 which will be described presently. The hangers are provided with hollow bosses 15, 15 arranged to receive attachments. Disposed centrally between the hangers 10 and 11 is a support 16 provided with a pair of 65 roller bearings 17, 17 separated by a suitable washer 18 to support a pair of co-axially mounted shafts 19 and 20. The outer ends of these shafts are mounted in bearings 22 and 23 provided in the hangers 10 70 and 11 respectively. For convenience we shall refer to the shaft 19 and its associated pulleys and other mechanism as 25 and the shaft 20 with its associated mechanism as 26. The unit 25 carries a pair of tight 75 pulleys 27 and 28 and a pair of loose pulleys 29, 29, and the unit 26 has a pair of loose pulleys 30, 30 and a pair of tight pulleys 31, 31. It will be understood that the tight pulleys are secured to the shaft by means of 80 set screws in order that when these pulleys are driven the connected parts will rotate with them. It will be seen that I have provided shafts having flattened portions arranged to be engaged by the set screws holding the tight pulleys. A pair of belt shifting devices 33 and 34 is provided for the unit 25. These belt shifting devices consist of a bellcrank lever having one arm connected with a slidable sleeve having a yoke 90 arranged to embrace a belt. By imparting movement to the free end of the bellcrank lever the belt will be shifted from the loose to the tight pulley. A pair of belt shifting devices 35 and 36 similar to those just described are provided for the unit 26. Extending through the hangers and the central support 16 on each side thereof are pairs of supporting rods 37, 37 and 38, 38, the object of which is to add sturdiness to the structure, 100 and also to provide supports for the belt shifting devices.

Referring to Fig. 5, I have shown a pair of machine benches 40 and 41, each mounting a bench lathe 42 and 43 having cone pulleys 105 45 and 46. The countershaft of my invention is shown at 47 disposed between a pair of uprights 48 and 49 extending from the machine bench supports. These uprights consist of pipe, and I have arranged so that 110

they may be inserted into the sleeves 12, 12 of the hangers and retained by means of set screws. Carried by the machine bench legs is an arm having a bearing to support a driving shaft 50 connected by means of a belt 51 to a motor 52 supported above the machine benches. The shaft 50 carries four pulleys 52, 53, 54 and 55, the pulleys 52 and 53 being disposed directly below the unit 25, 5 and the pulleys 54 and 55 are disposed below the unit 26. The pulleys 52, 53, 54 and 55 have belts 57, 58, 59 and 60 extending upwardly to connect with the loose pulleys 29 and 29 of the unit 25 and the loose pulleys 10, 30, 30 of the unit 26. As the connections are shown in the drawings, if the motor were in 15 operation and power being transmitted to the countershaft through the shaft 50, the loose pulleys would rotate without imparting motion to the cone pulleys 62 and 63 of the units 25 and 26. I have illustrated the shaft 50 as having pulleys of two different sizes, and by connecting the larger pulleys to their associated tight pulleys on the shaft, 20 a higher speed will be obtained than by connecting the smaller pulleys to their associated tight pulleys. The cone pulley 62 will have driving connection between it and the cone pulley 46, and the cone pulley 63 will 25 be connected to the cone pulley 45 of the bench lathe 42. Although I have described the countershaft as having but two speeds, it will appear that by the addition of additional driving pulleys and tight and loose 30 pulleys in the countershaft construction, it will be possible to provide an arrangement having more than two speeds, without departing from the spirit of my invention. The device shown at 70 in Fig 5 is a wheel

having bearings carried by a support secured 40 in the hollow bosses 15, and this wheel is arranged by means of a pulley carried on the shaft 73 to have connection with the pulley 74 of the unit 25. A similar pulley 76 is provided for the unit 26 to drive a 45 similar or other attachment carried by the hanger. I have found that this is a very convenient means of driving grinding machines or the like.

Having thus described my invention, what 50 I claim as new and desire to secure by Letters Patent of the United States is:

1. A countershaft construction comprising a pair of hangers, a supporting means therefor, a pair of pulley shafts having their axes substantially coaxial and their inner ends in proximity, a central support having a bearing for said inner ends, and a pair of supporting rods extending between the hangers and secured to the central support. 60

2. A countershaft construction comprising vertically extending supporting means, a pair of hangers adjustably supported on said supporting means, a pair of independently operable shafts having their axes substantially coaxial, a central bearing rigidly supported by means extending between the hangers, the inner ends of said shafts being supported by said central bearing and the outer ends of said shafts being supported by said hangers, whereby both of said shafts may be adjusted in vertical directions. 65

In witness whereof, I hereunto subscribe my name this 22nd day of January, 1918.

FRANKLIN HARDINGE.
